United States Patent

Des. 239,105

Patented Mar. 9, 1976

239,105

VEHICLE WHEEL

John Siroonian, Fresno, Calif., assignor to
Western U.S. Industries, Fresno, Calif.

Filed Sept. 13, 1974, Ser. No. 505,653

Term of patent 14 years

Int. Cl. D12—16

U.S. Cl. D12—205

Fig. 1.

Fig. 2.

FIG. 1 is a front elevational view of a vehicle wheel showing my new design;

FIG. 2 is a cross-sectional view thereof taken along line 2—2 in FIG. 1;

FIG. 3 is a rear elevational view thereof; and

FIG. 4 is a side elevational view thereof.

I claim:

The ornamental design for a vehicle wheel, as shown.
